FEED MODIFYING ATTACHMENT FOR SHOE
ROUNDING AND CHANNELING MACHINES

Telesphore E. Therriault, Manchester, N. H.

Application May 11, 1939, Serial No. 273,082

15 Claims.

(Cl. 12—18)

This invention relates to new and useful improvements in shoe machinery generally, and seeks to provide an attachment for channeling and rounding machines adapted during operation of the machine on crepe soles or the like to facilitate the feeding of such soles through the machines without causing abnormal wear on machine parts and without causing binding of engaging elements during the feed motions.

Heretofore, in working on crepe soled shoes with channeling and rounding machines, considerable difficulty has been encountered due primarily to increased drag or binding action on the machine feed elements. Many attempts have been made to eliminate or decrease this drag in a satisfactory manner, as by dusting chalk over the crepe soles or by spraying the soles with water in order to lessen the frictional resistance thereof during feeding. While these attempts have decreased to some extent the frictional resistance of the soles, it was found that abnormal loads were still imposed on various parts of the machines due to the increased forces applied thereto as a result of the compression of the crepe soles during feeding. In other words, it is necessary for the cooperating feed elements to grip the soles rather tightly in order to effect the proper feeding thereof, and in so doing the rubber of the soles is considerably compressed and the tendency of the soles to expand to normal thickness imposes the abnormal loading on and consequent wearing of certain parts of the machines.

This invention overcomes the above mentioned difficulties through the use of an attachment serving to provide a greater clearance between the machine feed elements during certain movements thereof.

In the normal manufacture of crepe soled shoes, one step in the production thereof consists in laying or attaching a medium crepe sole to the partly assembled shoe. This sole laying step immediately precedes the rough rounding operation. Then the work with the medium sole laid or attached is subjected to the rough rounding operation with which this invention deals. Next, the shoe goes to a "Goodyear" or other stitcher for the stitching operation which stitches the medium crepe sole to the welt thereby making a permanent attachment. Finally, an outer sole of heavier crepe rubber is cemented to the aforementioned medium sole, and then is edge trimmed to complete the work.

It is to be noted that this invention deals with means adapted to facilitate the rough rounding

operations on the first or medium crepe soles, and that due to the character of the work, there is no channeling of the medium crepe sole.

Therefore the principal object of the invention is to provide an attachment for channeling and rounding machines which is disposed in cooperative relationship with certain of the feed elements of said machines whereby the space intervening said feed elements will be automatically and intermittently increased a greater amount than normal to facilitate the feeding of crepe soled shoes without causing binding of the soles or abnormal wear of the various machine parts.

Another object of the invention is to provide a device of the above described character which may be rendered operative or inoperative by the operator as the character of the work demands.

A further object of the invention is to provide a device of the above described character which does not affect the normal operation of the channeling and rounding machine to which it is attached except to increase the feed spacing movements of the feed elements thereof to permit free feeding of crepe soled shoes.

A still further object of the invention is to provide a device of the aforementioned character which, in its inoperative or disengaged position, allows the channeling and rounding machine to which it is attached to function in its full normal manner.

With these and other objects in view which will more fully appear, the nature of the invention will be more clearly understood by following the description, the appended claims, and the several views illustrated in the accompanying drawings.

In the drawings:

Figure 1 is a side elevation illustrating the invention applied for use on a rounding machine.

Figure 2 is a fragmentary longitudinal vertical section of the machine.

Figure 3 is a fragmentary transverse section thereof taken on line 3—3 of Figure 2.

Figure 4 is a side elevation of the invention per se.

Figure 5 is a top plan view thereof.

Figure 6 is a detail section taken on line 6—6 of Figure 4.

Figure 7 is a detail section taken on line 7—7 of Figure 4.

Figure 8 is a detail section taken on line 8—8 of Figure 4.

The invention seeks to provide a novel free feeding attachment for conventional forms of

channeling and rounding machines, and more particularly for machines of the type disclosed in U. S. Letters Patent 1,030,606, issued to F. H. Perry on June 25, 1912. In the particular example of embodiment herein disclosed the invention is illustrated as applied to the particular form of machine mentioned, so much only of the patented machine as is necessary to illustrate the environment of the invention being included in this disclosure. In order to facilitate an understanding of the co-relation of the parts of the invention and the patented machine parts with which they cooperate, the patented machine parts will be referred to herein by the same reference characters employed to identify them in the patent.

The channeling and rounding machine above referred to includes a main cam shaft 21 journaled in the frame of the machine, and a disc cam 195 rigidly secured thereto. A rock shaft 267 is mounted in the machine frame for oscillatory and axial movement and is disposed above and to one side of the cam shaft 21. The rock shaft 267 has one end projecting beyond the machine frame and upon which is mounted a feed plate 5.

The feed plate 5 is given a four-motion movement through the following means. The rocking movements are imparted to the shaft 267 by a cam groove formed in the end of the cam disc 195 and engaging a cam follower 268 rotatably mounted on the end of an arm 269 secured to the shaft. The longitudinal movements are imparted to the shaft by a cam groove 270 formed in the periphery of the disc cam 195 and engaging a cam follower 271 carried by a sleeve 272 which surrounds the shaft 267. The sleeve is held against rotation by a depending longitudinal rib 273 engaging in a guideway formed in the frame of the machine.

A sole support 3 is disposed in cooperative relationship to the feed plate 5 for effecting a feeding of work through the machine, and is normally adapted to be given oscillatory movement through the medium of the following mechanism. The sole support is carried by a slide 183 which is mounted for vertical movement in a support 189 which is normally vibrated or oscillated in the direction of feed of the shoe. The support 189 is formed on the front end of a shaft 190 which is mounted to rock and move axially in bearings in the machine frame. A sleeve 191 is secured upon the shaft 190 and is provided with a flange 192 which engages the front bearing 193 for the shaft and limits the forward movement of the shaft and support. It is to be noted that the above described assembly can be moved a certain distance rearwardly for a purpose to be hereinafter described. The shaft 190 is rocked to oscillate the sole support by a cam groove 194 formed in the cam disc 195. The cam groove 194 engages a roll cam follower carried by one arm of a bell crank lever 196 which is mounted to rock upon the shaft 190. The other arm of the bell crank lever is provided with a projecting pin 197 which engages an arm projecting from the sleeve 191.

The sole support is constantly urged forward into yielding engagement with the surface of the sole by a spring which may be adjusted to apply various pressures thereto. The shaft 190, which carries the sole support, is pressed forward by a spring 198, the upper end of which is secured to an adjustable bolt 199, and the lower end of 75 which is connected to an arm 200 secured to a

rock shaft 201. A second arm 202 is secured to the rock shaft and is pivotally connected to a rod 203, the front end of which carries a head 204 engaging the end of a bore 205 in the shaft 190.

The sole support may be manually moved rearwardly in introducing or removing the work through a rock shaft 207, one end of which carries an arm 208 engaging a lug 209 on the sleeve 191. A bell crank lever 210 is secured to the rock shaft 207 and has one arm disposed for manual operation by the machine operator and the other arm connected by appropriate linkage to a foot treadle.

It is to be noted that the reference characters designating the invention per se extend from 30 15 to 44, and that the parts of the machine are given the reference characters used in the Perry Patent 1,030,606.

Devices are provided for varying the vertical position of the slide 183 and include a rock shaft 20 213 provided at its projecting forward end with an arm 30 rigidly secured thereto or integrally formed thereon and which is connected by a link 215 with the slide 183. The rock shaft 213 may be operated to raise the slide 183 by devices which 25 are operated to move the forepart guide into and out of operation and which are clearly shown in the Perry Patent 1,030,606. These devices include an arm 230 secured near the projecting rear end of the rock shaft 213 in abutting relation to the machine frame and which has the secondary function of restraining the shaft from forward axial movement. It is to be noted that when the attachment is disposed in operative position on the machine the forepart guide actuating devices which also vary the vertical position of the slide 183 are adjusted to the dead spot or position of no movement. The channel knife carried by the slide 183 is also maintained in its fully retracted position when the attachment is disposed in operative relation to the machine parts.

The invention modifies the movement of the support 189 from a straight oscillatory or vibratory movement to a four-motion movement in 45 order to provide the desired greater clearance between the feed plate 5 and the sole support 3 in effecting the proper feeding of crepe soled work without binding of the respective machine parts and said work. This is accomplished 50 through the medium of the following mechanism.

The rearwardly projecting end of the shaft 213 is provided with an arm 31 secured thereto, as by a set screw 32, and having its free end connected to the rear end of the rod 203. A sleeve 55 33 is secured to the shaft 213, as by set screws 34, and is disposed intermediate the frame bearings in which the shaft is journaled. An upwardly and rearwardly curved arm 35 is formed integrally with the sleeve 33, and is provided at 60 its free end with a flat offset portion 36 disposed adjacent the periphery of the cam disc 195 and parallel to the axis thereof. The offset portion 36 is provided with a longitudinally extending slot 37 adapted to receive the stud 38 of a roll 65 cam follower 39 adjustably secured therein by a nut 40. The cam follower 39 is adapted to engage the rear face of the disc cam 195 for approximately 240° of rotation, and then to engage an auxiliary cam plate 41 for the remaining 120° 70 of rotation. The cam plate 41 is secured to the rear face of the cam disc 195 and projects slightly beyond the plane of said face for a purpose to be hereinafter described.

An upwardly and forwardly extending arm 42 75

terminating in a short lateral projection 43 is secured to the forward side of the base of the arm 35, the projection 43 being disposed to overlie the upper portion of the sleeve 191 and engage the front face of the arm or projection formed thereon in the manner illustrated in Figures 1, 4 and 5 of the drawings.

5 A helical compression spring 44 encircles the shaft 213 and is disposed between the sleeve 33 and the rear frame bearing of the shaft. The spring 44 constantly tends to urge the sleeve and shaft forwardly thereby maintaining the cam follower 39 in contact with the cam disc 195.

In operation, the main cam shaft 21 and its 15 associated cam disc 195 are constantly rotated at a uniform ratio of speed. The feed plate 5 receives its four-motion movement as described through the cam followers 268 and 271, and at the same time the cam follower 39 associated 20 with the arm 35 is presented to and constantly urged against the rear face of the cam disc 195 through the expansion force of the spring 44. As the disc 195 rotates, the cam follower 39 will 25 engage the auxiliary cam face plate 41, thereby causing the follower, the arm 35 and its sleeve, and the arm 42 to be displaced rearwardly a distance equivalent to the amount of projection of the cam element 41 rearwardly of the rear face of said disc. This rearward movement of the 30 arm 35 is also transmitted to the sleeve 191 due to the engagement of the arm projection 43 therewith, and to the shaft 213, the arm 30 and the slide and block assembly 183, 189 due to the rigid connection of the sleeve 33 to said shaft. It 35 will be observed that the arms 30 and 31 carried by the shaft 213 also function as lateral braces between the shaft 213 and the slide mounting sleeve and assembly 190 to thereby minimize any 40 tendency for axial movement of the shaft 213 relative to the entire slide assembly.

This rearward movement of the slide and block assembly increases the distance between the feed plate 5 and the sole support 3 during the return movement following the feed movement, to thereby allow crepe soled work to be fed through the machine for rough rounding without binding and without placing overloads on the various machine parts.

The rearward movement of the shaft 213, by 50 virtue of the engagement of the arm 31 secured thereto and engaging the eye of the rod 203, also effects a rearward movement of the rod 203 and the resultant counteracting and relieving of the spring pressure on said rod.

55 The rough rounding is accomplished by the usual trimming knife given constant reciprocatory movement in timed relation to the feed movements through the medium of an eccentric and pivotal yoke connection to the knife carrying slide, as clearly shown in the Perry Patent 1,030,606.

The attachment can be rendered ineffective for producing the free feeding adjustment or feed motion modification above described by 60 merely releasing the nut 40 holding the cam follower 39 in operative relation to the disc cam 195 and sliding the follower away from the cam to thereby render the follower inoperative or out of contact with the cam. The machine will then 65 function in its normal manner on work not requiring the added feed clearance demanded when working on crepe soles. It is to be understood, of course, that the set screw 32 holding the arm 31 is released during the silencing of the attachment to thereby permit the arm to have move- 70

ment relative to the shaft 213 in order that the shaft may be permitted to partake of rocking motion in the vertical adjustment of the sole support during normal operations of the machine. It will be observed that when the set screw 32 is 5 released to permit the arm to have movement relative to the shaft 213, such movement of the shaft will also effect an oscillatory movement in space of the arms 35, 42 of the attachment.

It is to be noted that, if desirable, a solid block 10 may be used in working on crepe soles in place of the built up block or sole support 3.

Thus it will be seen that the invention provides means cooperatively related to the main cam disc of a channeling and rounding machine 15 of the type disclosed, whereby the free feeding of crepe soled work is facilitated.

It is of course to be understood that the details of structure and arrangement of parts may 20 be variously changed and modified without departing from the spirit and scope of my invention.

I claim:

1. In a shoe channeling and rounding machine, 25 a sole support, a feed plate spaced from and opposed to said sole support, means for imparting movement to said support and plate including a sole feeding movement together and a return movement including a period of relative movement normally effective for channeling purposes and a normal degree of separation for sole freeing purposes, and means operable during said return movement for bringing about a greater than normal degree of movement 30 of separation to adapt the machine for work upon 35 soles of crepe rubber or the like.

2. In a shoe channeling and rounding machine, 40 a sole support, a feed plate spaced from and opposed to said sole support, means including a rotary cam for imparting movement to said support and plate including a sole feeding movement together and a return movement including a period of relative movement normally effective for channeling purposes and a normal degree of movement of separation for sole freeing purposes, 45 and means actuated by said cam and operable during said return movement for bringing about a greater than normal degree of movement of separation to adapt the machine for work upon 50 soles of crepe rubber or the like.

3. In a shoe channeling and rounding machine, 55 a sole support, a feed plate spaced from and opposed to said sole support, means including a rotary cam for imparting movement to said support and plate including a sole feeding movement together and a return movement including a period of relative movement normally effective for channeling purposes and a normal degree of movement of separation for sole freeing purposes, and means actuated by said cam and operable 60 during said return movement for bringing about a greater than normal degree of movement of separation to adapt the machine for work upon soles of crepe rubber or the like, said last named means including devices movable out of the zone 65 of influence of the cam for silencing said last named means and restoring the machine to normal operation.

4. In a shoe channeling and rounding machine, 70 a sole support element, a feed plate element spaced from and opposed to said sole support element, rotary cam actuated means for imparting movements to said support element and plate element including a sole feeding movement together and a return movement including a period 75

- of relative movement normally effective for channeling purposes and a normal degree of movement of separation of one said element relative to the other for sole freeing purposes, and 5 additional means actuated by said cam and operable during said return movement for effecting a degree of movement of separation of the other said element relative to the first to adapt the machine for work upon soles of crepe rubber or 10 the like.
5. In a shoe channeling and rounding machine, a sole support element, a feed plate element spaced from and opposed to said sole support element, rotary cam actuated means for imparting 15 movements to said support element and plate element including a sole feeding movement together and a return movement including a period of relative movement normally effective for channeling purposes and a normal degree of movement 20 of separation of one said element relative to the other for sole freeing purposes, and means actuated by said cam and operable during said return movement for effecting a degree of movement of separation of the other said element 25 relative to the first to adapt the machine for work upon soles of crepe rubber or the like, said last named means including devices movable out of the zone of influence of the cam for silencing 30 said last named means and restoring the machine to normal operation.
6. In a shoe channeling and rounding machine, the combination of a feed plate, a sole support spaced from and opposed to said feed plate, means including a rotary cam for moving said feed plate towards said sole support for gripping work therebetween, means for simultaneously moving said feed plate and said sole support in one direction to effect a feeding of work held therebetween then to effect a return movement 40 of said sole support relative to said feed plate and then to effect a return and spacing movement of said feed plate relative to said sole support back to the initial condition, and means actuated by said cam for increasing the distance 45 between said sole support and said feed plate an amount greater than normal during the return movements thereof to thereby permit crepe soled shoes to be fed through the machine without binding the various machine parts.
7. In a shoe channeling and rounding machine, a sole support element, a feed plate element spaced from and opposed to said sole support element, rotary cam actuated means for imparting 50 movements to said support element and plate element including a sole feeding movement together and a return movement including a period of relative movement normally effective for channeling purposes and a normal degree of movement of separation of said feed plate relative to said sole support for sole freeing 55 purposes, and additional means actuated by said cam and operable during said return movement for effecting a degree of movement of separation of said sole support relative to said feed plate to 60 adapt the machine for work upon soles of crepe rubber or the like.
8. In combination with a shoe channeling and rounding machine including, a frame, a rotary cam, a sole support, a shaft journaled in the 65 frame and carrying said sole support, an upstanding lug secured to said shaft, said shaft being operatively connected to said cam, a feed plate spaced from and opposed to said sole support and operatively connected to said cam, 70 means including a rock shaft normally effective

to vary the vertical position of said sole support, an arm secured to said rock shaft and having its free end disposed in close proximity to said cam and parallel to the axis thereof, a cam follower mounted on said arm, a cam plate mounted 5 on one face of said cam and projecting beyond the plane of said face, a second arm secured to said first mentioned arm and adapted to engage said lug on said sole support carrying shaft, the cam follower being adapted to engage 10 the face of said cam then engage said cam plate to thereby move said arms, said rock shaft and said support carrying shaft axially to effect a movement of separation of said sole support relative to said feed plate to adapt the machine for 15 work upon soles of crepe rubber or the like.

9. In combination with a shoe channeling and rounding machine including, a frame, a rotary cam, a sole support, a shaft journaled in the frame and carrying said sole support, an upstanding lug secured to said shaft, said shaft being operatively connected to said cam, a feed plate spaced from and opposed to said sole support and operatively connected to said cam, means including a rock shaft normally effective 20 to vary the vertical position of said sole support, an arm secured to said rock shaft and having its free end disposed in close proximity to said cam and parallel to the axis thereof, a cam follower mounted on said arm, said follower being 25 adjustably mounted relative to said cam to vary the degree of movement of the follower by the cam, a cam plate mounted on one face of said cam and projecting beyond the plane of said face, a second arm secured to said first mentioned arm and adapted to engage said lug on said sole support carrying shaft, the cam follower being adapted to engage the face of said cam then engage said cam plate to thereby move said arms, said rock shaft and said support carrying 30 shaft axially to effect a movement of separation of said sole support relative to said feed plate to adapt the machine for work upon soles of crepe rubber or the like.

10. In combination with a shoe channeling and rounding machine including, a frame, a rotary cam, a sole support, a shaft journaled in the frame and carrying said sole support, an upstanding lug secured to said shaft, said shaft being operatively connected to said cam, a feed 40 plate spaced from and opposed to said sole support and operatively connected to said cam, means including a rock shaft normally effective 45 to vary the vertical position of said sole support, an arm secured to said rock shaft and having its free end disposed in close proximity to said cam and parallel to the axis thereof, a cam follower mounted on said arm, said follower being adjustably mounted relative to said cam to vary the degree of movement of the follower by the cam, 50 a cam plate mounted on one face of said cam and projecting beyond the plane of said face, a second arm secured to said first mentioned arm and adapted to engage said lug on said sole support carrying shaft, the cam follower being 55 adapted to engage the face of said cam then engage said cam plate to thereby move said arms, said rock shaft and said support carrying shaft axially to effect a movement of separation of said sole support relative to said feed plate to adapt 60 the machine for work upon soles of crepe rubber or the like, said cam follower being movable out of the zone of influence of said cam to render 65 the spacing movement of said sole support inoperative.

11. In combination with a shoe channeling and rounding machine including, a frame, a rotary cam, a sole support, a shaft journaled in the frame and carrying said sole support, an upstanding lug secured to said shaft, said shaft being operatively connected to said cam, a feed plate spaced from and opposed to said sole support and operatively connected to said cam, means including a rock shaft normally effective 5 to vary the vertical position of said sole support, an arm secured to said rock shaft and having its free end disposed in close proximity to said cam, a cam follower mounted on said arm, a cam plate mounted on one face of said cam and projecting beyond the plane of said face, a second arm secured to said first mentioned arm and adapted to engage said lug on said sole support carrying shaft, the cam follower being adapted to engage the face of said cam then engage said cam plate 10 to thereby move said arms, said rock shaft and said support carrying shaft axially to effect a movement of separation of said sole support relative to said feed plate, said sole support adjusting means including a third arm having one end secured to the forward end of said rock shaft and its other end secured to said sole support, said third arm serving to add rigidity to 15 the entire assembly during axial movement of said rock shaft and said sole support under the urge of said cam.
12. In a shoe channeling and rounding machine, a frame, a rotary cam, a shaft journaled in the frame, a sole support mounted for normal vertical adjustment on the forward end of said shaft, the shaft being operatively connected to said cam, an upstanding lug secured to said shaft, said shaft being operatively 20 connected to said cam, a feed plate spaced from and opposed to said sole support and operatively connected to said cam, means including a rock shaft normally effective to vary the vertical position of said sole support, an arm secured to said rock shaft and having its free end disposed in close proximity to said cam and parallel to the axis thereof, a cam follower mounted on said arm, a cam plate mounted on one face of said cam and projecting beyond the plane of said face, a second arm secured to said first mentioned arm and adapted to engage said lug on said sole support carrying shaft, the cam follower being adapted to engage the face of said cam then engage said cam plate 25 to thereby move said arms, said rock shaft and said support carrying shaft axially to effect a movement of separation of said sole support relative to said feed plate, said sole support adjusting means including a third arm having one end secured to the forward end of said rock shaft and its other end secured to said sole support, a fourth arm having one end secured to the rear end of said rock shaft and its other end connected to said sole support urging means, said third and fourth arms serving to add rigidity to the entire assembly during axial movement of said rock shaft and said sole support 30 under the urge of said cam, said fourth arm also serving to counteract the pressure of said sole support urging means.
13. In a shoe channeling and rounding machine, a frame, a rotary cam, a shaft journaled in the frame, a sole support mounted for normal vertical adjustment on the forward end of said shaft, the shaft being operatively connected to said cam, an upstanding lug secured to said shaft, a feed plate spaced from and opposed to said sole support and operatively connected to said cam, means including a spring for constantly urging said sole support carrying shaft forwardly, means including a rock shaft normally effective during 35 channeling operations to vary the vertical position of said sole support, an attachment adjustable between operative and silenced conditions for adapting the machine for work on crepe soled shoes and including an arm secured to said rock shaft and having its free end disposed in close 40 proximity to said cam, a cam follower mounted on said arm, a cam plate mounted on one face of said cam and projecting beyond the plane of said face, a second arm secured to said first mentioned arm and adapted to engage said lug on said sole support carrying shaft, the cam follower being adapted to engage the face of said cam then engage said cam plate to thereby move said arms 45 said rock shaft and said support carrying shaft axially to effect a movement of separation of said sole support relative to said feed plate, said sole support adjusting means including a third arm having one end secured to the forward end of said rock shaft and its other end secured to said sole support, a fourth arm having one end secured to the rear end of said rock shaft and its other end connected to said sole support urging means, said third and fourth arms serving to add rigidity to the entire assembly during axial movement of said rock shaft and said sole support 50 under the urge of said cam, said fourth arm also serving to counteract the pressure of said sole support urging means.
14. In a shoe channeling and rounding machine, a frame, a rotary cam, a shaft journaled in the frame, a sole support mounted for normal vertical adjustment on the forward end of said shaft, the shaft being operatively connected to said cam, an upstanding lug secured to said shaft, a feed plate spaced from and opposed to said sole support and operatively connected to said cam, means including a spring for constantly urging said sole support carrying shaft forwardly, means including a rock shaft normally effective during 55 channeling operations to vary the vertical position of said sole support, an attachment adjustable between operative and silenced conditions for adapting the machine for work on crepe soled shoes and including an arm secured to said rock shaft and having its free end disposed in close 60 proximity to said cam, a cam follower mounted on said arm, a cam plate mounted on one face of said cam and projecting beyond the plane of said face, a second arm secured to said first mentioned arm and adapted to engage said lug on said sole support carrying shaft, the cam follower being adapted to engage the face of said cam then engage said cam plate to thereby move said arms said rock shaft and said support carrying shaft axially to effect a movement of separation of said sole support relative to said feed plate, said sole support adjusting means including a third arm having one end secured to the forward end of said rock shaft and its other end secured to said sole support, a fourth arm having one end secured to the rear end of said rock shaft and its other end connected to said sole support urging means, said third and fourth arms serving to add rigidity to the entire assembly during axial movement of said rock shaft and said sole support 65 under the urge of said cam, said fourth arm also serving to counteract the pressure of said sole support urging means.
15. In a shoe channeling and rounding machine, a frame, a rotary cam, a shaft journaled in the frame, a sole support mounted for normal vertical adjustment on the forward end of said shaft, the shaft being operatively connected to said cam, an upstanding lug secured to said shaft, a feed plate spaced from and opposed to said sole support and operatively connected to said cam, means including a spring for constantly urging said sole support carrying shaft forwardly, means including a rock shaft normally effective during 70 channeling operations to vary the vertical position of said sole support, an attachment adjustable between operative and silenced conditions for adapting the machine for work on crepe soled shoes and including an arm secured to said rock shaft and having its free end disposed in close 75 proximity to said cam, a cam follower mounted on said arm, a cam plate mounted on one face of said cam and projecting beyond the plane of said face, a second arm secured to said first mentioned arm and adapted to engage said lug on said sole support carrying shaft, the cam follower being adapted to engage the face of said cam then engage said cam plate to thereby move said arms said rock shaft and said support carrying shaft axially to effect a movement of separation of said sole support relative to said feed plate, said sole support adjusting means including a third arm having one end secured to the forward end of said rock shaft and its other end secured to said sole support, a fourth arm having one end secured to the rear end of said rock shaft and its other end connected to said sole support urging means, said third and fourth arms serving to add rigidity to the entire assembly during axial movement of said rock shaft and said sole support under the urge of said cam, said fourth arm also serving to counteract the pressure of said sole support urging means.

proximity to said cam, a cam follower mounted on said arm, a cam plate mounted on one face of said cam and projecting beyond the plane of said face, a second arm secured to said first mentioned arm and adapted to engage said lug on said sole support carrying shaft, the cam follower being adapted to engage the face of said cam then engage said cam plate to thereby move said arms said rock shaft and said support carrying shaft axially to effect a movement of separation of said sole support relative to said feed plate, said sole support adjusting means including a third arm having one end secured to the forward end of said rock shaft and its other end secured to said sole support, a fourth arm having one end secured

to the rear end of said rock shaft and its other end connected to said sole support urging means, said third and fourth arms serving to add rigidity to the entire assembly during axial movement of said rock shaft and said sole support under the urge of said cam, said fourth arm also serving to counteract the pressure of said sole support urging means, said support adjusting means including a lever arm secured to said rock shaft and disposed intermediate said last named arm and the machine frame in abutting relation to said frame, whereby forward axial movement of said rock shaft will be prevented. 5 10 15

TELESPHORE E. THERRIAULT. 15
